(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

[The sole FIGURE is] FIG. 1 shows a display screen or portion thereof with graphical user interface showing our new design; and,

FIG. 2 is a second embodiment thereof.

The peripheral dashed broken lines [represent] illustrate a display screen or portion thereof which forms no part of the claimed design.

**1 Claim, 2 Drawing Sheets
(1 of 2 Drawing Sheet(s) Filed in Color)**

Matter enclosed in heavy brackets [ ] appears in the original patent but forms no part of this reissue; matter printed in italics indicates the additions made by reissue.
